MECHANISM FOR DRAWING OR DRAFTING FIBROUS MATERIAL

Filed April 13, 1921

2 Sheets-Sheet 2

UNITED STATES PATENT OFFICE.

ARTHUR CECIL BUTLER, OF BOSTON, MASSACHUSETTS.

MECHANISM FOR DRAWING OR DRAFTING FIBROUS MATERIAL.

Application filed April 13, 1921. Serial No. 461,139.

(GRANTED UNDER THE PROVISIONS OF THE ACT OF MARCH 3, 1921, 41 STAT. L., 1313.)

To all whom it may concern:

Be it known that I, ARTHUR CECIL BUTLER, a subject of the King of Great Britain, and residing at Boston, in the county of 5 Suffolk and State of Massachusetts, have invented new and useful Improvements in Mechanism for Drawing or Drafting Fibrous Material, for which I have filed applications in Great Britain, July 27, 1914, 10 Patent No. 17699 of 1914, and in Canada, May 31, 1920, application No. 241,830, of which the following is a specification.

This invention has relation to the drawing of rovings and has for its object to provide 15 a simple improvement in the drawing mechanism of drawing, fly, or spinning frames.

In the drawing mechanism of such instrumentalities, the roving is passed between separated pairs of rolls and the rolls of the 20 several pairs are rotated at increasing speeds in the direction of travel of the roving so as to draw out the fibers and elongate the roving. The fibers which compose the roving are of different lengths and it frequently occurs 25 in the ordinary draft mechanism that the yarn is delivered in an uneven and bumpy condition, this being caused to some extent by the longer fibers drawing along with them some of the shorter fibers so that 30 the draft is uneven.

The present invention provides means by which a very long draft may be attained in a single stage while the evenness of the yarn is maintained. This construction makes possible 35 the production of fine yarn from the rovings with a minimum number of passes through the drawing mechanism and consequently eliminates the necessity of many of the spindles heretofore used to receive the 40 yarn intermediate the several drawing operations since the roving and fine roving frames may be rendered unnecessary even for spinning fine counts of yarn.

The mechanism provided according to this 45 invention is applicable at any stage in the manufacture of fibrous material after the fibers have been arranged in substantially parallel relation as in the form of a lap, ribbon, sliver, or roving, for example, after 50 the material has been carded or after the process of drawing as performed in a draw-

ing frame, but it is particularly applicable to drawing the material just prior to the spinning operation, the mechanism as shown being designed as a substitute for the drafting rolls hitherto employed in spinning frames. 55

More particularly this invention provides means for restraining the passage of the roving between successive drawing rolls to 60 retain the fibers in general parallel relation and to prevent the shorter fibers from bunching as the roving is passed through the mechanism.

For a more complete understanding of this 65 invention reference may be had to the accompanying drawings in which—

Figure 1 is a somewhat diagrammatic side elevation of one form of the mechanism.

Figure 2 is a fragmentary plan of the same 70 parts.

Figure 3 is a side elevation illustrating a modified form of mechanism assembled on the roll stand.

Figure 4 is a fragmentary plan of some of 75 the parts shown in Figure 3.

Figure 5 is a diagrammatic side elevation illustrating a third form of mechanism.

Figure 6 is a diagrammatic side elevation illustrating two mechanisms similar to those 80 shown in Figures 3 and 4 arranged for successive operation on the roving.

Figure 7 is a diagrammatic side elevation which illustrates a further modification.

Referring to Figures 1 and 2, *a* and *b* 85 represent the bottom and top front rolls, respectively. The second and back rolls ordinarily employed are omitted and in place of the lower roll is positioned a roll *c* having a covering *C* of leather or other suitable material. This roll may be supported so as to be adjustable vertically and laterally from the front roll *a* in any suitable way.

On the roll *c* is placed a flexible cap or 90 cover *d* formed of flexible sheet steel or other resilient, hard, and smooth material. This cap *d* is curved to conform on its concave surface to the circumference of the roll *c*. The back part of the cap *d* is preferably strengthened by a thicker piece of metal or 100 other reinforcement *e* and is heavily weighted while the front part *f* exerts a graduated

weight or pressure on the roll by reason of its resilience. The strengthening piece *e* which may conveniently be brazed or soldered to the resilient part of the cap *d* is shown as having secured to it a conical or trumpet mouthed centering guide *g* for the roving and the metal of the resilient part is continued up the rear of the strengthening piece *e* to the sides of the guide *g* so that the rear of the cap *d* presents a rounded surface to the roving passing beneath it. At its front the cap *d* is shown as having its corners turned down so as to converge at the front into an upright position to form a concentrating or condensing guide *h*.

As illustrated in Figures 1 and 2 the strengthening piece *e* is in the form of a tray conforming on its lower surface to the shape of the cap *d* and formed into a socket shaped to receive a presser foot *i* carried by a lever *j* having a screw threaded arm *k* adjustably secured in position by nuts *l*, *m*, in a socket *n*. This socket is pivoted on an arm *o* projecting laterally from a stud *p* which is adjustably threaded in the roll carrying beam *s*, nuts *q* and *r* being provided for fastening the stud in adjusted position. If desired the presser foot *i* may be made separate from the lever *j* and be furnished with a socket to receive a rounded or knife edged part of the lever *j* so that the foot *i* may be able to oscillate relatively to the lever *j*. Ears *t* are shown as provided upon the sides of the piece *e* at either side of the socket therein to embrace the sides of the presser foot *i* and thereby to keep the cap *d* in position laterally relative to the lever *j*.

The upper part of the arm *k* has formed therein a hole *u* through which the rear of the cap *d* and the guide *g* may project in order that the lever *j* may bear centrally upon the cap *d* without interfering with the passage of the roving from the rear along the central line of the cap.

As shown the lever *j* is provided with a hook *v* to which is attached a cord or chain *w* led over a guide rod *x* supported in any convenient way. This cord *w* is led through a hole *y* in the beam *s* and may have a weight (not shown) attached thereto to press the foot *i* against the reinforcing piece *e* of the cap.

The roving to be drawn is laid as indicated by the dotted lines *A* and arrows *B* through the guide *g* between the roll *c* and the cap *d* and through the guide *h* to the rolls, *a*, *b*.

The roll *c* and the roll *a* are driven by any suitable means so that the peripheral speed of the rolls *a* and *b* is greater than that of the roll *c* so as to exert the requisite drawing action upon the roving delivered by the roll *c* and held back by the cap *d*. The arrows shown on the several rolls *a*, *b*, and *c* indicate the directions in which they are made to revolve.

The lever *j* holds the cap *d* against movement with the roll *c* and the nuts *l*, *m*, *q*, and *r* enable the position of the cap upon the roll *c* to be adjusted. From the rolls *a*, *b* the roving may be led to a spindle or ring traveler in which it may be spun, or it may be subjected to further drawing by passage through mechanism similar to that already described as may be desired.

In the form shown in Figures 3 and 4 the cap *d* is shown as provided with a pad *z* and screws *1* enabling adjustment of the graduated pressure exerted by the cap *d*. Also the lever *j* is shown as provided with a forked end *2* embracing a rod *3* resting in guides *4*, one of these guides only being shown. These guides take the place upon roll stands ordinarily occupied by the bearing brackets of the usual back bottom roll of a ring spinning frame or mule and provide for some adjustment of the lever *j* in the cap *d*. A filling piece *6*, changeable for another of different thickness, or for two or more, is shown as inserted in the forked end *2* of the lever *j* to bear upon the rod *3* to provide for further adjustment of the position of the cap relative to the roll *c*. In this construction the lever *j* being positioned above the guide *g* is not provided with a hole for the passage of the roving since the roving may pass to the guide *g* at either side of the lever *j* or beneath the rod *3*. The lever *j* is weighted by means of a hook *7* made to embrace it above a pair of shoulders *8*, this hook permitting passage of the roving to the guide *g* and having suspended from its lower end by means of a hook *9* extending through the hole *y* in the roll beam *s*, a suitable weight (not shown).

The reinforcement *e* is also made to extend forwardly and is turned down at its forward end *10* and is provided on either side with downwardly extending ears *11* to form a socket *12* in which the pad *g* of felt or other suitable compressible material is placed as well as a plate *13* bearing on the pads *e* and engaged by the screws *1* by which pressure is exerted thereon. These screws are adjustable to regulate the relative pressures exerted by different parts of the cap *d* against the roving.

As shown in Figure 3 also the roll *c* may be adjusted within the guide *14* by means of a series of interchangeable filling pieces *15* inserted beneath the bearing *16* for the roll. The brackets *14* are also designed to be adjustable to and from the rolls *a* and *b*.

In Figure 5 is shown a further modification in which the cap *d* is provided with a pair of bearing plates *13* and adjusting screws *9* for each bearing plate for exerting pressure upon a resilient arm or plate *f* which as shown is shaped to conform on its

lower surface to a roll cover of leather or similar material C'' which passes like a belt partly around the circumference of the roll c and another preferably smaller roll 17 placed close to the roll c. The roll c preferably may be adjustable similarly to the roll c shown in Figures 3 and 4, and the roll 17 is also made adjustable and suitably weighted to apply tension to the cover C''. As shown this tensioning of the covering C'' is provided by trunnions 18 on the roll 17 mounted to revolve in jaws 19 in one arm of a pair of bell crank levers 20, one of which only is shown, the other arms of these levers being connected to a weight (not shown). These arms are fulcrumed on a rod 22 by means of jaws 21 taking thereover.

Figure 6 shows a further modification in which are used two sets of rolls c and c' and caps d and d' generally similar to those illustrated in Figures 3 and 4, but with two pressure plates and adjusting screws like those shown in Figure 5. These sets of rolls are arranged so that one set delivers the roving passed therethrough to the second set in order that it may be further operated upon so that the roving may be drawn in two stages. Corresponding parts of the second or front set are distinguished from the parts of the first or back set by the exponent 1. The roll c' of the front set is made to revolve at a surface speed higher than that of the roll a of the rear set and the front roll a' of the front set is made to revolve with a surface speed greater than that of the roll c'. The cap d' is therefore between the nips of the two sets of rolls a, b and a' and b'.

In Figure 7 a further modification is shown in which rolls c, c' and caps d, d' similar to those shown in Figure 6 are arranged in series, the first or back cap d being placed below the mating roll c so that this roll is made to revolve in the opposite direction to that of the second roll c', the parts otherwise being operated identical to the construction shown in Figure 6. In a similar manner more than two rolls c with corresponding caps d may be arranged to operate on the roving in succession.

In each case it is noted that the roving passing from one roll to another and beneath the various caps is subjected to as little deflection as possible and also that the relative positions of the parts are adjustable to suit the requirements of different kinds or grades of material. The condensing guide g provided at the entering edge of each cap brings the edges of the roving toward the center so reducing the tendency of the fibers to escape from the edges but if it is preferred this guide may be omitted. Likewise, if desired, the concentrating guide h for the delivery end of the cap may be omitted. It will also be understood by those skilled in the art that many other changes and modi-

fications may be made without departing from the spirit and scope of this invention as defined by the appended claims.

I claim:

1. A mechanism for drawing fibrous material, comprising the combination with a pair of coacting rolls and a roll for delivering the fibrous material thereto, of a cap concavely curved to fit against said last-mentioned roll, and exerting pressure against said fibrous material. 75

2. A mechanism for drawing fibrous material, comprising the combination with a pair of coacting rolls and a roll for delivering the fibrous material thereto, of a cap concavely curved to fit against said last-mentioned roll, said cap being resilient and exerting diminishing pressure against said fibrous material. 80

3. A mechanism for drawing fibrous material, comprising the combination with a pair of coacting rolls and a roll for delivering the fibrous material thereto, of a cap concavely curved to fit against said last-mentioned roll and exerting pressure against said fibrous material, and means for exerting pressure against said cap. 85 90

4. A mechanism for drawing fibrous material, comprising the combination with a pair of coacting rolls and a roll for delivering the fibrous material thereto, of a cap concavely curved to fit against said last-mentioned roll and exerting pressure against said fibrous material, and means on which said cap may rock. 95

5. A mechanism for drawing fibrous material, comprising the combination with a pair of coacting rolls and a roll for delivering the fibrous material thereto, of a cap concavely curved to fit against said last-mentioned roll and exerting pressure against said fibrous material, said cap having a guide at one end. 100 105

6. A mechanism for drawing fibrous material, comprising the combination with a pair of coacting rolls and a roll for delivering the fibrous material thereto, of a cap concavely curved to fit against said last-mentioned roll and exerting pressure against said fibrous material, said cap being provided with a condensing guide at one end, 110 and a guide at its other end. 115

7. In a drawing mechanism, the combination with means for supporting and feeding a roving, of a cap cooperating with said supporting means and exerting pressure along a length of the roving, said pressure being greater at one end than at the other end of said length. 120

8. In a drawing mechanism, the combination with means for supporting and feeding a roving, of a cap cooperating with said supporting means and exerting pressure along a length of the roving, said pressure being greater at the drawing end than at the delivery end of said length. 125 130

9. A mechanism for drawing fibrous material, comprising the combination with a pair of coacting rolls and a roll for delivering the fibrous material thereto, of a cap 5 concavely curved to fit against said last-mentioned roll and having a free end extending toward the nip of said pair of rolls.

10. A mechanism for drawing fibrous material, comprising the combination with a 10 pair of coacting rolls and a roll for delivering the fibrous material thereto, of a cap concavely curved to fit against said last-mentioned roll and exerting pressure against said fibrous material, said cap consisting of 15 a flexible metallic plate having a free end extending toward the nip of said pair of rolls.

11. A mechanism for drawing fibrous material, comprising the combination with a 20 pair of coacting rolls and a roll for delivering the fibrous material thereto, of a cap concavely curved to fit against said last-mentioned roll and having a free end extending toward the nip of said pair of rolls, 25 and means for holding said cap in place.

12. A mechanism for drawing or drafting cotton or other fibrous material, comprising, in combination with a roll, a cap and means by which said cap exerts a pressure at or 30 near the place of first contact of fibrous material with the cap or cover which gradually diminishes from the back toward the front, substantially as and for the purpose hereinbefore described.

13. A mechanism for drawing or drafting cotton or other fibrous material as claimed in claim 12, characterized by a thicker piece 35 of metal or reinforcement at the part of the cap at which pressure is applied, substantially as and for the purpose hereinbefore described.

14. A mechanism for drawing or drafting cotton or other fibrous material as claimed in claim 1, characterized by a pad and a 45 plate, and adjusting means for said plate for adjusting the graduation of the pressure of the cap against the roll with which it is used, substantially as and for the purpose hereinbefore described.

15. In a drawing mechanism for roving, a plate arranged to rest loosely by gravity on the roving between the nips of adjacent pairs of rolls.

16. In a drawing mechanism, two pairs of 55 drawing rolls, a plate arranged to rest by gravity on the roving between the rolls, and means for loosely attaching the plate in place.

17. In a drawing mechanism for roving, 60 a plate arranged to rest loosely by gravity on the roving between the nips of adjacent

pairs of rolls, and means for supporting the roving and coacting with the plate to afford a frictional resistance to the roving.

18. In a drawing mechanism for roving, a 65 plate arranged to rest loosely by gravity on the roving between the nips of adjacent pairs of rolls, and having a condensing guide at its end portion.

19. In a drawing mechanism, the combination with a pair of drawing rolls, and movable means for feeding and supporting a roving during its travel to the nip of said rolls, and a gravity plate to rest on the roving while it is so supported. 70

20. A drawing mechanism for roving comprising spaced pairs of drawing rolls driven at different speeds, a traveling surface between the nips of said rolls, and a loosely fitted cap or plate pressing the roving 80 against said surface.

21. In a drawing mechanism, the combination of two pairs of drawing members, comprising top rolls and cooperating bottom rolls, and a loosely hinged gravity cap 85 resting on the roving between the nips of said rolls.

22. A drawing mechanism comprising front and rear pairs of top and bottom rolls, an intermediate bottom roll, and a gravity 90 cap resting loosely upon said intermediate roll and under which the roving passes.

23. In a drawing mechanism, the combination with a pair of drawing rolls, means for feeding and supporting a roving during its travel to the nip of said rolls, and means for exerting a retarding effect on said roving while so supported variable lengthwise thereof. 95

24. In a drawing mechanism, the combination with a pair of drawing rolls, means for feeding and supporting a roving during its travel to the nip of said rolls, and means for exerting a retarding effect on said roving while so supported diminishing toward 100 the nip of said rolls.

25. In a drawing mechanism, the combination of two pairs of drawing members, comprising top rolls and cooperating bottom rolls, and a loosely hinged gravity cap resting on the roving between the nips of said rolls, said cap being provided with a roving guide at its outer edge. 110

26. In a drawing mechanism, the combination with a drawing roll, of a cap or plate 115 cooperating therewith to press the roving thereagainst, and means for adjusting said cap or plate about the axis of said roll.

In testimony whereof I have affixed my signature.

ARTHUR CECIL BUTLER.
